UNITED STATES PATENT OFFICE.

JAMES O. BLAKE, OF GARY, INDIANA.

RAILROAD-TIE.

1,105,955.

Specification of Letters Patent.

Patented Aug. 4, 1914.

Application filed May 4, 1914. Serial No. 836,271.

To all whom it may concern:

Be it known that I, JAMES O. BLAKE, a citizen of the United States, residing at Gary, in the State of Indiana, have invented 5 a new and useful Improvement in Railroad-Ties, of which the following is a specification.

My objects are to provide an economical construction of railroad tie, and to provide 10 means on the tie, integral therewith, for securing rails in place thereon.

Referring to the accompanying drawings, Figure 1 is a view in elevation of a tie constructed in accordance with my invention, a 15 portion of the tie being broken away, and the rails applied to the tie shown in section. Fig. 2 is a plan view of one end of the tie showing a rail in position thereon. Fig. 3 is an end view of the tie, showing by a view 20 in side elevation a rail positioned thereon; and Fig. 4, a perspective view of one end of the tie.

In carrying out my invention I provide a pair of heads, or chairs, 6, spaced apart from 25 center to center a distance equal approximately to the distance from center to center of the rails to be used with the tie. These chairs may be of any suitable construction, but I prefer to form them of steel members 30 of H-shape in cross-section with upwardly converging ends as shown, affording at their lower flanges 7 relatively long seating surfaces forming bearings for the tie on the road-bed, and at their upper flanges 8 relatively short seating surfaces for the rails. 35 The form of chair shown is especially desirable, as it may be cut from a bar of steel without any appreciable waste, and while presenting sufficient bearing surfaces at its 40 upper and lower portions for all practical requirements, involves the use of the minimum amount of material.

The chairs 6 are secured together, preferably at their upper and lower flanges 8 and 45 7, respectively, by bars 9 and 10, these bars being preferably formed of steel and each comprising a base-portion 11 formed with a strengthening rib 12 extending longitudinally thereof. The bars 9 and 10 overlap, 50 at their bases 11, the flanges 7 and 8 of the chairs and are secured thereto as by rivets 13 passing through the bases 11 and the flanges of the chairs which they overlap. The form of bar which I prefer to employ

is of T-shape in cross-section, the ribs 12 of 55 which in the case of the upper bars 9 being preferably shorter than the base-portion 11 of these bars, and of such length that their ends, when the rails are applied to the ties in properly gaged position, will reach a slight 60 distance short of the webs of the rails represented at 14. The ribs 12 of the upper bars 9 are preferably recessed at their ends immediately above the base-portions 11, as represented at 15, for receiving the inner flanges 65 16 of the rails 14, the inner edges of these flanges bearing against the innermost walls of these recesses.

The tie is provided with means for holding the rails 14 in place thereon, these means 70 by preference, being formed integrally with the bars 9 and comprising lips 17 formed on the ends of the base-portions 11 of these bars beyond the rails and adapted to be bent upwardly and inwardly to overlap the 75 outer flanges 18 of the rails and coöperate with the recessed portions 15 of the bars 9 for clamping the rails in place on the tie.

Where the rail-clamping means just described are employed, the ties may be disengaged from the rails by bending the lugs 17 upwardly and outwardly away from the flanges 18, and as repeated manipulation of the lugs 17 in the event of repeated unfastening of the rail, might produce a weakening of the lugs 17, I prefer to provide two sets of the lugs 17, formed by slitting the ends of the base-members 11 of the bars 9, whereby a reserve set of these lugs is provided. 90

It will be understood from the foregoing that the chairs 6 are firmly held against undue displacement on the road-bed, by means of the bars 9 and 10, which, by reason of their formation with ribs extending at angles to their base-portions, may be of comparatively light weight and still present a high degree of resistance to stresses tending to flex them. 95

In the form shown, the ends of the ribs 100 12 of the bars 9, at their recessed portions, form means for preventing the inner flanges 16 of the rails from rising, the end-portions of these ribs also serving as abutments for the inner flanges 16 of the rails; and while 105 it is desirable that the rails abut against the innermost walls of these recesses, the abutment may, if desired, be between the ex-

treme outer ends of these ribs and the webs of the rails 14, or against both portions of these ribs.

It will be understood from the foregoing description that a tie constructed in accordance with my invention will be of comparatively light weight, but possess a high degree of rigidity and stiffness and resistance to stresses exerted by a train passing over the rails.

While I prefer to form the bars 9 and 10 of T-shape form in cross-section, it will be readily understood that any other suitable form of strengthening rib may be employed to permit relatively light weight bars to be used.

What I claim as new, and desire to secure by Letters Patent is—

1. A railroad tie composed of chairs spaced apart longitudinally of the tie, and upper and lower bars connecting said chairs together, formed with longitudinally-extending ribs.

2. A railroad tie composed of chairs spaced apart longitudinally of the tie, and upper and lower bars connecting said chairs together, and formed of base-portions and

longitudinally-extending ribs, said bars being connected at their base-portions with said chairs.

3. A railroad tie composed of chairs spaced apart longitudinally of the tie, and upper and lower bars overlying at their ends the top and bottom surfaces of said chairs and connected therewith.

4. A railroad tie composed of chairs of metal of approximately H-shape in cross-section, affording upper and lower flanges forming seating surfaces, and means connecting said chairs together in spaced relation.

5. A railroad tie composed of chairs of metal of approximately H-shape in cross-section, affording upper and lower flanges forming seating surfaces, and upper and lower bars overlying at their ends the top and bottom surfaces of said upper and lower flanges, respectively, and connected therewith.

JAMES O. BLAKE.
